O. MITCHELL.
CASE FOR CIGARETTES OR THE LIKE.
APPLICATION FILED JULY 12, 1916.

Patented Aug. 21, 1917.

UNITED STATES PATENT OFFICE.

OLIVER MITCHELL, OF NEEDHAM, MASSACHUSETTS, ASSIGNOR TO WEBSTER COMPANY, OF NORTH ATTLEBORO, MASSACHUSETTS, A CORPORATION OF RHODE ISLAND.

CASE FOR CIGARETTES OR THE LIKE.

1,237,540.

Specification of Letters Patent. Patented Aug. 21, 1917.

Application filed July 12, 1916. Serial No. 108,937.

To all whom it may concern:

Be it known that I, OLIVER MITCHELL, a citizen of the United States, residing at Needham, in the county of Norfolk and State of Massachusetts, have invented new and useful Improvements in Cases for Cigarettes or the like, of which the following is a specification.

My invention is a case especially adapted 10 for carrying matches, cigars, cigarettes or the like, and consists of a flat outer case or box, made in two parts the two parts being hinged together at one side and provided with a catch to keep the two parts closed 15 when desired.

Within the outer case is suspended a base, upon which may be mounted any sort of holder that may be desired; the base being suspended and connected to the outer case 20 in such fashion that, when the outer case is opened, it will be lifted and held centrally between the two parts of the outer case. The base and holder may of course be an integral, unitary part.

25 In the drawings:

Figure 1 is a view of the case in closed position, partly in section;

Fig. 2 is the same, the case being in open position;

30 Fig. 3 is a perspective view of the base;

Fig. 4 is a view of the case, open;

Fig. 5 is a top view of the case, closed; and

35 Figs. 6 and 7 are views in section, of a modified form, in open and closed positions.

The object of my invention is to provide a case which will be of simple construction, economical to make and which will, in operation, when the outer case is opened, automatically center, lift and present the inner holder upon the base and when the two halves or lids of the outer case are pressed together will automatically lower and retire the inner holder on its base.

40 I accomplish this by hanging the base upon links, which at their outer ends are attached to the inner sides of the outer case so that, as the case opens, the links go from the vertical position in which they stand before the case is opened, into approximately 45 horizontal position, lifting the base and its holder in relation to the lids and permitting perfect access to the holder for the purpose

of filling the holder or taking an article therefrom.

55 In the form shown in Figs. 1, 2 and 4, I employ as links, springs, which may serve the double function of supporting and lifting the base, and that of throwing open the outer case when the catch is disengaged. 60 These springs are "set" in the process of making, to approximately the shape shown in Fig. 2.

65 In these figures the two lids forming the outer case are marked respectively A and B and these parts are hinged together at *a*. Upon those sides of the lids A, B, which abut where the parts are hinged together, a stop is preferably formed upon the outside, as at *b*, which limits the opening movement of the parts upon the hinge, so that they will only separate a predetermined distance, say, until an angle of 90° between the two parts, has been reached, as shown in Fig. 2.

70 Within the two outer lids are springs S, which are secured at their ends *x* to the lids A, B, the springs S being mounted toward the free ends of the lids. The other ends of these springs S are secured to the base C. 80 When the outer case is closed it is obvious that these springs will be bent as seen in Fig. 1 and that, in this position, the distorted spring will be under maximum strain and tend constantly to throw the outer case 85 open, since, when the catch D of the outer case is opened, the springs S will tend to straighten out, as seen in Fig. 2, to the shape to which they were originally "set" and, in so doing, will throw the lids A, B, open 90 until they are stopped by the surface, *b*, contacting or by any other suitable stop.

95 Mounted upon the springs S and securely fastened thereto is the base C, for the inner holder. At the opposite side of the lids, A, B, from that at which they are hinged together, the catch D is provided to hold the two lids together when the case is closed, against the effort of the springs S, which tend constantly to throw the lids 100 open.

105 In Figs. 6 and 7 I have illustrated a modification in which ordinary pivoted links S' are made use of, instead of the spring links S. In this form a hinge spring, *a'*, is employed to throw open the lids A, B, and thus

lift the base, C, and holder, H, into position. Preferably a short extension S^x is provided on link S' which when the case is open impinges on the under side of the base, to steady the same.

The operation is as follows: The case being opened as shown in Figs. 2 and 4 the inner holder may be filled with cigarettes or other articles, which it is desired to carry, and the case is then closed by bringing the parts A and B together and engaging the catch D. When the lids A and B are closed together, the end, x, of each link attached to the lids, is brought over the other end of the link and the link itself into a position parallel with the sides of the inner holder H and the other links, and the base C is lowered toward the hinge, a, of the case A, B. When the case A, B, is permitted to open, the separation of the lids A, B, tends to draw each link into a lengthwise relation with the opposite link of the pair, lifting and centering the base and holder.

25 The flexible and resilient link has the advantage for certain uses over the ordinary link, shown in Figs. 6 and 7, that each link S performs the functions of the links S' and in addition requires no pivots and also 30 each link S performs the function of the spring a' shown in Figs. 6 and 7.

I have shown in the drawings, Figs. 1, 2 and 4 and have described in the specification, the inner member C as a carrier upon

which any desired holder might be mounted. 35 It is obvious, that in certain cases, no special holder would be required, as, when the base was shaped to receive some particular article, for example, a box of cigarettes, which when emptied would be removed and a full 40 box substituted. In general, however, some form of holder would be mounted upon and secured to the base or made integral therewith.

I claim:

1. In a cigarette case or the like, a pair of hinged lids; a base; a pair of spring-links connecting with and suspending the base between said lids.
2. A cigarette case or the like including 50 hinged lids, a base arranged within the case, and links connecting the base and lids to elevate the base in the open movement of the lids, the links being connected to the base at approximately the lowest point 55 thereof and being of a length to cause a substantial lifting of the base in the opening of the lids, the links holding the base in spaced relation to the lids in all positions of the parts and compelling a movement of 60 the base free of possible contact with the lids.

Signed by me at Boston, Mass., this 28th day of February, 1916.

OLIVER MITCHELL.
